TIMING DEVICE

Clarence L. Elder, Baltimore, Md., assignor to Elder Systems Corporation, Baltimore, Md., a corporation of Maryland

Filed May 13, 1963, Ser. No. 280,029
4 Claims. (Cl. 194—4)

The present device relates to a timing device and is a continuation-in-part of my application for Letters Patent filed in the U.S. Patent Office December 21, 1962, Serial No. 247,468, now abandoned.

The primary object of the invention is to provide a device for measuring time for the future operation of a service, machine and the like, in which the time period is substantially longer than is normally customary in most timing operations such as, weekly, bi-weekly or monthly.

A further object of the invention is to provide a novel and fool-proof mechanism to carry out the primary object of the machine.

Another object of the invention is to provide a token type control element that is only usable in operation and has no value for other purposes.

A still further object of the invention is to provide tokens of different control features for different time periods.

Still another object of the invention is to provide means by which an additional period of time may be added after the time period on the token has expired before the cycle of the timing device is completed.

While several objects have been set forth, other objects, uses and advantages will become more apparent as the nature of the invention is more fully disclosed, which consists in its novel construction, arrangement and combination of its several parts illustrated in the accompanying drawings and described in the detailed description to follow.

In the drawings:

FIGURE 1 is a diagrammatical vertical view of the timing device.

FIGURE 2 is a diagrammatical fragmentary view of the contact carrying member C shown in FIGURE 1.

FIGURE 3 is a diagrammatical fragmentary vertical view on a reduced scale of the token carrying channel, showing two tokens within the channel.

FIGURE 4 is a sectional view of the token.

In describing the invention, like character references are used to point out like and similar parts throughout the several views.

The device is provided with a frame such as shown at 10 for supporting the timer mechanism and a housing, such as shown at 12 for enclosing the device.

One of the principal features of the timing mechanism is carried out by the operation of an electric motor 14, in that, the motor is adapted to rotate a token 15 at a very slow rate. When the electric current is supplied to the motor 14, the small gear 20 carried by the motor 14 is rotated, which in turn rotates the larger gear 22. The gear 22 is either fixed or rotated about a shaft 24. Adapted to rotate with the gear 22 is a small angular gear 26, which operates a larger angular gear 28. The gear 28 is either fixed or rotated about a shaft 30 carried in the portion 10' of the supporting frame. Adapted to be rotated by the gear 28 is a worm gear (not shown) which is adapted to engage the gear 32. The gear 32 is supported upon a shaft 34, which is supported by the frame portion 10''. Secured to the shaft and/or the gear 32 is a gear 36 which in turn is adapted to engage gear 38. Gear 38 is supported upon the shaft 40 which is slidably supported on the frame portion 10'''. The slide shaft 40 is provided with an extended pin portion 42. This pin portion is adapted to extend through an aperture 44

2

of the token 15. The pin portion 42 is provided with means such as splines for engaging the token and rotating the same. The shaft 40 is slideable perpendicular to the plane of the circular token element in order to engage the aperture and rotate the token 15 when the token is in position to be operated and to withdraw the token to the position shown by the dotted lines 15' and out of its operating position and in a position to be discharged into a suitable token collection tray (not shown). The pin 42 and the shaft 40 are operated by a suitable slow operating solenoid 48.

The operation of the device is primarily controlled by a time control unit 50. This time control unit 50 is adapted to be automatically movable back and forth along the radius of the token adjacent at least one face thereof and supported upon a track 52 from its position shown in full lines to the position shown in dotted lines at 50'.

The time control is electrical operated and is supplied with electric current through the bracket member 54, of which the face adjacent the element 50 is provided with means of making electric contact therewith. The bracket 54 is constructed of some non-conductive material such as "Bakelite," having metal conductor strips 57, 58, and 59 against which spring loaded contact elements carried by the time control unit 50 are in contact as the element is moved along the rack 52, current being supplied to the bracket 50 through the wire 66.

Referring again to the token 15, it is provided with a recessed spiral groove 46 and may have one or more spirals about the token. In FIGURE 3 only one spiral is shown, however, the face of the token may have in place of the spiral groove a magnet path which may be charged to operate similar to a magnet tape to control the downwardly movement of the time control unit 50.

The device is adapted to operate on ordinary 110 volt current which is fed into a conventional transformer 59 by lead wires 60 and 62 where the voltage is substantially reduced and fed therefrom through wire 64 to the frame of the device and the wire 66 to the time control unit 50 through the slide contact bracket member 54.

The unit 50 through its electrical sliding connection with the member 54 controls the operation of the motor 14 through wire 67 for rotating the token as previously described. The unit 50 also carries mechanisms for moving itself up the rack 52 for any number of predetermined downward trips over the face of the same token periods through means of a stepping switch 43. The unit also carries means for energizing the solenoid 48 for moving the end 42 into the opening 44 of the token and for withdrawing the shaft 40 from the opening 44 in the token and for withdrawing the token to a discharge position as shown by dotted line 15 in FIGURE 1. The unit 50 may also carry a mechanism such as a delaying action switch for causing the unit 50 to remain at a predetermined place for a certain period of time referred to as a "grace period" prior to breaking the electric circuit carried by wire 70 to the apparatus it is designed to control.

For simplicity the electric circuit is a single wire system, using the frame as the negative or ground wire as shown in wire 64.

Referring particularly to FIGURE 3 the tokens are conveyed into position by guide members 71 and 72. The tokens are provided with a channel 73 which is adapted to straddle a bar 74 to keep the tokens in a definite position when they are injected into the device. That is, as shown, the starting position of the time control unit 50 is preferably at the outer end 46' of the recessed spiral groove 46, which is at the outer end of the spiral, the time control unit 50 being adapted to work toward the center of the token, that is, the unit 50 starts in

the position as shown by the dotted lines 50' in FIGURE 1 and moves to the position as shown in full lines at 50.

Referring again to FIGURE 3, the guide members 71 and 72 are adapted to receive one or more tokens as shown at 15' and 15''. In order to prevent the token 15'' from interfering with the operation of token 15' stop 75 is provided to support the token 15'' out of contact with the token 15''. The object being, that at times it may be advantageous to place two or more tokens in the device to cause the apparatus to operate consecutively from one token to the other which, of course, would increase the operation period of the apparatus being operated.

The machine may be constructed in multiple form whereby the same driving means and other general functions may be utilized to operate two or more timing mechanisms in which two or more tokens may be used at the same time for timing the operation of two or more separate electric switches which in turn control the operation of a particular apparatus.

The device is adapted for use with all kinds of apparatus such as gas meters, washing machines, radios, television etc. and is connected thereto by a suitable outlet 73 and a wire 76. However, any type of connection with the device may be used.

In its operation, the unit 50 may be normally positioned adjacent the rotatable axis of the token and at the position where it is shown in full lines. By inserting a token 15, the token will operate a switch 78 which is connected to the unit 50 by the wire 71. Mechanisms within the unit 50 will cause the solenoid 48 to become energizing by operating an electric contact which will send a current out through one of the metal strips on the member 54, and through wire 65, which will in turn energize the solenoid 48 and the shaft to be extended into the aperture 44 of the token, and at the same time current will be supplied to the motor 14 through wire 67 which will in turn rotate the token at a very slow predetermined speed. The rotating speed of the token may be as slow, or as fast as the situation demands. In FIGURE 3 of the present drawings, the token is designed to rotate once every twenty-four hours. At the same time a finger 51 carried by the time control unit 50 is backed off and the unit 50 moves to a position as indicated by the dotted line 50', when the finger 51 is extended toward the token and engages the outer recessed end 45' of the open groove 45 at which time the disk starts its rotation by the operation of the motor 14 as previously described, moving the unit 50 toward the center of the token according to the degree of the spiral recess.

If the unit 50 is provided with a stepping switch, the unit may repeat its operation as often as the step switch is set for. Upon the last movement of the unit 50 towards the center by the tokens the circuits to the apparatus may be immediately broken, or retained for a definite time, by the time delaying switch. However, the solenoids may be energized after the unit 50 has made its last inward trip to withdraw the token and position it to be deposited into the token collection tray and also operate to place a new token in position within the timing device.

While a specific structure of an invention has been illustrated and specifically pointed out in the written description it is not intended as a limitation and therefore the scope of the invention is best defined in the appended claims.

I claim:

1. A timing device for governing the future operation of an electric switch including a frame and housing for supporting and enclosing a mechanism therefor, said mechanism comprising in combination:

(a) a rotatable time governing token of relatively narrow width formed with a pair of flat substantially parallel side faces and of substantially round configuration having means adjacent its center adapted to engage on operating element therefor;

(b) a time control unit having a token engaging element adapted to be movable back and forth over a predetermined path and extending over at least the radius of the token adjacent one of the faces of the token and in a plane parallel therewith;

(c) said token having a spiral groove in at least one face thereof for slidably receiving the token engaging element for producing at least one movement of the back and forth motion of the time control unit;

(d) means operated by the token engaging element for operating said electric switch;

wherein the time for future operation of the electrical switch is governed by the groove in the face of the rotatable token.

2. In a timing device as claimed in claim 1 wherein means are provided for repeating the travel of the time control unit over the face of the same token and means for operating the electrical switch at the end of its last controlled travel of the timing device by the token.

3. In a timing device as claimed in claim 1 wherein means are provided for the operation of the electrical switch at a predetermined time after the time control unit has been moved to the end of its controlled movement by the token.

4. A timing device for governing the future operation of an electric switch including a frame and housing for supporting and enclosing a mechanism therefor, said mechanism comprising in combination:

(a) a rotatable time governing token of relatively narrow width formed with a pair of flat substantially parallel side faces and of substantially round configuration having means adjacent its center adapted to engage an operating element therefor;

(b) a channel for receiving one or more tokens and for delivering single tokens into operating position in the timing device and means for supporting the adjacent token out of contact position with the token in operating position;

(c) a time control unit having a token engaging element adapted to be movable back and forth over a predetermined path and extending over at least the radius of the token adjacent one of the faces of the token and in a plane parallel therewith;

(d) said token having a spiral groove in at least one face thereof for slidably receiving the token engaging element for producing at least one movement of the back and forth motion of the time control unit;

(e) means operated by the token engaging element for operating said electric switch

wherein the time for the future operation of the electrical switch is governed by the groove in the face of the rotatable token.
